UNITED STATES PATENT OFFICE.

ELIZABETH JANE SMITH, OF LARCHMONT, NEW YORK.

PRONGED EYE FASTENER.

1,416,902.

Specification of Letters Patent. Patented May 23, 1922.

Application filed March 4, 1915. Serial No. 12,054.

To all whom it may concern:

Be it known that I, ELIZABETH J. SMITH, a citizen of the United States of America, residing in Larchmont, in the county of 5 Westchester and State of New York, have invented certain new and useful Improvements in Pronged Eye Fasteners, of which the following is a specification.

The present invention relates to improvements in pronged fasteners, more particularly to a pronged eye fastener which is complementary to a hook fastener, and aims to provide improvements therein.

The present invention provides a pronged eye fastener which is especially adapted to be attached to dress fabrics, both heavy and light, which may be attached to the fabrics without mutilating the same, which may be firmly attached, and which will not tear the fabric or separate therefrom under the usual stresses to which a fastener of this kind may be subjected.

The present invention also provides a fastener which is cheaply and readily manufactured, which may be conveniently removed in fitting a garment, or the like, and which co-operates well with a hook fastener.

The present fastener is also specially adaptable for setting by machine.

The invention will be described in greater detail in reference to the accompanying drawing.

In said drawing—

Figure 1 is a perspective view of the 35 fastener;

Fig. 2 is a top plan view with the prongs spread out;

Fig. 3 is a top plan view showing the fastener attached to a piece of fabric;

Fig. 4 shows a cross-section on the line IV—IV in Fig. 3, the prongs being in standing position;

Fig. 5 shows a cross-section on the line V—V in Fig. 3, and

Fig. 6 shows a bottom plan view of the fastener attached to a piece of fabric.

In said drawings, numeral 1 designates a bar which is adapted to be engaged by the hook, 2, 2 laterally projecting portions or 50 shoulders, and 3, 3 the prongs. The bar 1 is preferably bowed upwardly in its middle, as indicated at 4 in Fig. 5. The bar 1 is also preferably provided with inwardly cut or curved sides 5, 5, Fig. 2. A hook engaging 55 the bar 1 may pass under the upwardly bowed bar 1, and will center itself and fit

symmetrically upon the incurved side 5 of the bar. The length of the bar 1, i. e., the distance between the prongs, and the curvature of the sides, is preferably adapted to the bill 60 of the hook, the length of the bar being slightly greater than the width of the bill of the hook. The laterally projecting portions or shoulders 2, 2 afford a broad, flat 65 and secure bearing for the fastener on the face of the goods. The prongs 3, 3 are long and narrow and when bent over upon the underside of the goods are adapted to well overlap, without being superposed, and to firmly press the goods throughout their 70 length against the broad underside of the fastener afforded by the laterally projecting portions or shoulders 2, 2. When set in the manner just described, the prongs fix the 75 fasteners securely to the goods, and the fastener will sustain the usual stresses to which it is subjected without loosening, or tearing the goods. Furthermore, the goods are not mutilated by the fastener. If it is desired to re-set the fastener, as, for instance, after 80 a fitting of a garment, the prongs can be lifted with a suitable implement and the fastener removed.

What is claimed is—

1. An eye fastener formed of integral 85 sheet metal, with a hook-engaging bar, laterally-projecting base portions at the opposite ends thereof constituting a substantially H-shaped piece, and tapering prongs bent perpendicularly from the ends of said base portions, so that when passed through a fabric and flattened down they may clamp the fabric between themselves and such base portions, the hook-engaging bar being humped upwardly at its middle above the plane of 90 said base portions, the lateral base portions being of a length approximating their distance apart, whereby the prongs enter the fabric at four widely separated points located in approximation to the corners of a 95 square.

2. An eye fastener formed of integral 105 sheet metal, with a hook-engaging bar, laterally-projecting base portions at the opposite ends thereof constituting a substantially H-shaped piece, and tapering prongs bent perpendicularly from the ends of said base portions, each of a length approximating the length of such base portions, oppositely tapered so that when passed through a fabric and flattened down they may lie side by side and clamp the fabric between themselves 110

and such base portions, the hook-engaging bar being humped upwardly at its middle above the plane of said base portions, the lateral base portions being of a length approximating their distance apart, whereby the prongs enter the fabric at four widely separated points located in approximation to the corners of a square.

In witness whereof, I have hereunto signed my name in the presence of two subscribing 10 witnesses.

ELIZABETH JANE SMITH.
